UNITED STATES PATENT OFFICE.

CHARLES DRAPALIK, OF OMAHA, NEBRASKA.

DRAIN-BOARD BRACKET.

1,262,468.

Specification of Letters Patent.

Patented Apr. 9, 1918.

Application filed September 27, 1916. Serial No. 122,501.

To all whom it may concern:

Be it known that I, CHARLES DRAPALIK, a citizen of the United States, residing at Omaha, in the county of Douglas and State 5 of Nebraska, have invented new and useful Improvements in Drain-Board Brackets, of which the following is a specification.

This invention relates to means for removably securing a drain board to either 10 side of a sink.

The object of the invention is to provide a means as above stated and further provide a means by which the drain board may be adjusted to regulate its inclination.

15 The invention further resides in the novel means employed for adjustably securing one end of the drain board directly to the sink, the securing means being such as to permit of the adjustment of the outer end of the 20 board to any desired angle.

With the above objects in view the invention consists of a drain board provided at one of its edges with a screw clamp, a pair of bars having opposed serrated faces, one 25 of said bars being secured to a lug formed on the lower edge of the sink and being provided with apertures, the other bar being secured to a lug on the underside of the board and being provided with an elongated 30 slot, to receive a fastening means carried by the first mentioned bar.

In the drawings;

Figure 1 is a front elevation of a sink of the roll type having the invention applied 35 thereto;

Fig. 2 is an edge view of the same;

Fig. 3 is a perspective view of one of the bars; and

Fig. 4 is a similar view of the other bar.

40 In the application of the invention there is provided upon the underside of the sink 1 lugs 2. These lugs are preferably four in number there being two of said lugs located upon the opposite edges of the sink. The 45 drain board shown at 3 may be of the usual construction, and is provided upon one of its edges with an undercut portion 4 adapted to conform to the roll edge of the sink.

A suitable fastening means consisting of 50 a screw clamp 5 is carried by the board 3 and is adapted to engage the underside of

the roll of the sink when in position. It is of course obvious that one or more of these clamps may be employed as desired.

Located near the opposite end of the 55 board are a pair of lugs 6, having pivoted thereto one bar of a brace 8. This brace is provided with a serrated face 9 for engagement with the serrations 10 formed on the bar 11. The last named bar is pivoted to 60 one of the lugs 2 previously mentioned. Apertures 13 are provided in the bar 11 and are adapted to carry a fastening means 14, which may consist of a bolt or screw. The fastening means 14 is adapted to be 65 passed through a slot 15 formed in the bracket 7 so as to provide means for extending said bracket to control the angle at which the board 3 may be set.

By reference to Fig. 2 of the drawings it 70 will be seen that there are preferably employed two of the braces 8, in order to insure a more stable support for the board.

It will be seen from the foregoing that the invention provides an efficient means for 75 adjustably securing a drain board to either end of the sink, and doing away with the necessity of supporting the sink by brackets fastened to the wall. This last mentioned means has been found unsatisfactory owing 80 to the crumbling away of the plastering and the consequent weakening of the supporting brackets.

Having described the invention, what I 85 desire to claim and secure by Letters Patent, is;

The combination with a drain board having adjustable supporting braces pivotally secured to one end thereof for engagement with the sink, of a clamp carried by the opposite end of said board, said clamp including a stationary member formed by providing a concave seat in the end of the board, an adjusting screw located adjacent one edge of said seat, an arm loosely mounted 90 upon said screw and co-operating with said seat, whereby this end of the board may be adjustably secured to the sink and a nut mounted upon the screw for holding the arm 95 in its adjusted position.

100 In testimony whereof I affix my signature.
CHARLES DRAPALIK.
